(57) **CLAIM**

The ornamental design for a cubby for vehicle interior, as shown and described.

DESCRIPTION

FIG. 1 is a perspective view of a cubby for vehicle interior showing our new design;

FIG. 2 is a top view thereof;

FIG. 3 is a front view thereof;

FIG. 4 is a rear view thereof;

FIG. 5 is a right side view thereof; and,

FIG. 6 is a left side view thereof.

The broken lines and de-emphasis in the figures are used to represent portions of the cubby for vehicle interior that form no part of the claimed design.

1 Claim, 3 Drawing Sheets
